CAN TRANSFER AND ORIENTING
MECHANISM

Andrew L. Christiansen, Willowbrook, Calif.

Application July 4, 1944, Serial No. 543,448

4 Claims. (Cl. 198—33)

1

My invention relates to a can transfer and conveying mechanism.

One of the principal objects of this invention is to provide relatively simple and efficient means for transferring cans, particularly cans open at one end, from one conveyor to another, so that the cans may be conveyed with their openings directed upwardly.

An important object also of this invention is to provide a mechanism of this class in which cans which are lying on their sides, and open at one end (that is, with the openings of the cans on the side), are turned with such openings directed upwardly, and in which such turning of the cans is effected while transferring the cans from one conveyor to another.

An important object also of this invention is to provide a novel means for turning an article from one position to a position substantially at right angles thereto.

A further important object of this invention is to provide a mechanism of this class in which the turning operation is performed with a minimum of vibration or shock to the can and the contents therein, and particularly while the can is being received and transferred from a conveyor.

With these and other objects in view, as will appear hereinafter, I have devised a mechanism for transferring and conveying cans, and one having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a side elevational view of my can transfer and conveying mechanism, in a preferred form, for transferring cans from a can packing machine to a conveyor;

Fig. 2 is a fragmentary transverse sectional view taken through 2—2 of Fig. 1, showing the first stage for receiving the cans from the packing machine, and initially and partially tilting the same in their path toward the ultimate conveyor, a can being shown in a partly tilted position;

Figs. 3 and 4 are fragmentary transverse sec-

2

tional views thereof, taken through 3—3 and 4—4 of Fig. 1, showing intermediate stages in the tilting or turning of the packing cans in the transfer mechanism, Fig. 3 showing by dotted lines a can in a slightly greater tilted position than that shown in Fig. 2; and,

Fig. 5 is a fragmentary end elevational view of the transfer mechanism from which the cans are discharged to a conveyor in upright position, a can being shown on such conveyor.

My present machine is an improvement of United States Patent No. 2,195,882, issued to me, April 2, 1940, for a "Can packing machine." The frame 1, the can conveyor 2, mounted thereon, and the packing conveyor 3 also mounted on the frame, are similar to those shown in the above patent. Only the discharge ends of these conveyors are here shown. The discharge end of the conveyor 2 is shown as carried on a sprocket 15 4 which is mounted on a shaft 5, revolvably supported in a horizontal position at one end of the frame 1.

The conveyor 2 consists primarily of a continuous series of transverse blocks 2^a carried by a link belt 2^b. The adjacent sides of the blocks have semi-cylindrical recesses which together form a cylindrical pocket. In each of such cylindrical pockets is positioned a correspondingly shaped can. This can, designated C, with one 25 end of the can open, and which has been previously packed by this machine with a suitable product, is carried in such pocket, transversely of the longitudinal extent of the conveyor. The blocks 2^a, when carried around the discharge 30 end of the conveyor, are separated, as shown, causing the pocket to be opened and allowing the can between the adjacent blocks to be carried by the leading block until it assumes a 35 receding and inclined position, as the block designated 2^a. The can carried by the block is then 40 discharged, or allowed to fall by gravity, from the cradle of the carrying block.

My present invention relates to a mechanism which receives the packed cans in a lying position, that is, with the opening at the side, from the aforementioned conveyor, and turning the same, with the openings of the cans directed upwardly, and depositing the same on another conveyor.

Such turning mechanism, as shown in the

drawings, consists primarily of a helical passageway embodied in an open chute 11. This chute extends from the discharge end and in the direction of the conveyor 2, but downwardly therefrom. It consists of a plurality of rectangular frames 11^a which are connected by a plurality of twisted strips or guides 11^b. These strips or guides are so twisted that the passageway within the chute assumes the shape of a helix, for receiving, at the high end of the chute, the cans in a lying position from the conveyor 2, tending to cause the same, aided by the force of gravity, to be directed toward the opposite or low end of the chute, and to be gradually turned from a lying position to a substantially upright position at said lower end. The arrangement of the strips or guides, as shown best in the enlarged section in Fig. 4, may consist of a bottom strip or guide and two strips or guides at the opposite sides.

The cans are retained in the path of the blocks 2^a, at the discharge end of the conveyor 2, and also at a slight angle backwardly, by a guard 12 which is supported by the frame 1 beyond the discharge end of the conveyor 2. The cans C fall from the cradles in the blocks 2^a against the guard 12, and as the blocks are withdrawn from the guard, the cans drop toward the receiving end of the chute. At the opposite sides of the guard 12 are other guard plates 13 for locating the ends of the cans and definitely guiding the cans into the chute.

In order to facilitate the transfer of the cans from the conveyor 2 to the chute 11, I have provided a pair of link belts or chain conveyors 14 and 15 immediately below the discharge end of the conveyor 2, these belts 14 and 15 extending into the receiving end of the chute 11. The end of the upper stretches of the belts 14 and 15, positioned under or near the discharge end of the conveyor 2, are of the same height, that is, they are horizontal with respect to each other, but the opposite or lower ends of these belts, that is, the ends extending into the chute 11, are such that the conveyor 15 is lower than the conveyor 14. The cans drop on the horizontal ends of the belts 14 and 15, and are thereby given an initial turn in the direction of the helical passageway of the chute.

In order to carry out such arrangement of the belts, the receiving end of the belts 14 and 15 extend around like diameter sprockets 16 mounted on the shaft 17. The opposite ends of the upper stretches of these belts respectively extend around a large sprocket 18, and a smaller sprocket 19, both mounted on the same shaft 20. These belts are of the same length and are held taut by idler sprockets 21 and 22, arranged on different axes, substantially as shown in Fig. 1.

Both of these link belts or chain conveyors are provided with stops or lugs 23 for checking the progress of the cans and feeding the same individually from the conveyor 2 through the chute 11 onto the receiving conveyor 24.

The cans may be deposited directly from the chute 11 onto the conveyor 24. There may be provided a guard (not shown) at the side of the conveyor 24 to prevent the cans from being projected beyond the latter conveyor.

Though I have shown and described a particular construction, combination, and arrangement of parts and portions, I do not wish to be limited to the same, but desire to include in the scope of my invention the construction, com-

bination, and arrangement substantially as set forth in the appended claims.

I claim:

- 5 1. In a mechanism of the class described, a pair of horizontal conveyors, the first having means for holding cans transversely with respect to the longitudinal extent of the latter conveyor and for conveying the same, means for transferring said cans from the latter conveyor to a substantially upright position on the other conveyor, said means comprising a downwardly inclined helical passageway of substantially rectangular cross-section for receiving at one end the cans transversely therein from the first conveyor and in substantially the positions of the cans on said first conveyor, said passageway directing said cans toward the opposite end thereof and simultaneously turning the same so that they may be deposited in said substantially upright position on the other conveyor, and a third conveyor positioned at the bottom of the receiving end of the helical passage means, the upper stretch of the third conveyor being inclined to conform to the downward inclination of the helical passage means, one end of the third conveyor being positioned below the discharge end of the first conveyor for receiving cans in substantially horizontal positions from the first conveyor, the upper portion of the opposite end of the third conveyor being inclined transversely at substantially the transverse angle of the helical passage means into which said end of the third conveyor extends, the third conveyor having longitudinally spaced partitions for receiving singly the cans from the first conveyor.
- 10 2. In a mechanism of the class described, a conveyor having means for holding cans transversely with respect to the longitudinal extent thereof, and for conveying the same, means in association therewith for receiving said cans from said conveyor and turning the same upwardly at an angle, said means comprising a helical passageway of substantially rectangular cross-section for receiving said cans one end thereof from said conveyor and directing the same toward the opposite end thereof and simultaneously turning said cans so that they may be turned in a substantially upright position at said opposite ends, and a second conveyor positioned at the bottom of the receiving end of the helical passage means, the upper stretch of the conveyor being inclined downwardly, one end of the second conveyor being positioned below the discharge end of the first conveyor for receiving cans in substantially horizontal positions from the first conveyor, the upper portion of the opposite end of the second conveyor being inclined transversely at substantially the transverse angle of the helical passage means into which said end of the second conveyor extends, the second conveyor having longitudinally spaced partitions for receiving singly the cans from the first conveyor.
- 15 3. In a mechanism of the class described, a pocket conveyor having transverse pockets for conveying cans on the side, another conveyor positioned below the former for receiving the cans and partly turning the same with one end upwardly, a guard extending around the discharge end of the first conveyor for directing cans sidewise to said second conveyor, and a downwardly inclined helical chute for receiving cans sidewise from the second conveyor and rotating the same to an upright position.
- 20
- 25
- 30
- 35
- 40
- 45
- 50
- 55
- 60
- 65
- 70
- 75

4. In a mechanism of the class described, a pocket conveyor comprising an endless chain having transverse pockets therein and a wheel around which the discharge end of said chain extends, cans adapted to be placed sidewise in the pocket and adapted to be discharged therefrom when said cans are positioned substantially laterally from the axis of said wheel, another conveyor positioned below the former for receiving the cans and partly turning the same with one end upwardly, a guard extending around the discharge end of the first conveyor for directing the cans sidewise to said second conveyor, and a downwardly inclined helical chute for receiving

ing cans sidewise from the second conveyor and rotating the same to an upright position.
